DESIGN FOR A CASKET HANDLE

Paul Lester Parsons, Belvidere, Ill.

Application March 13, 1935, Serial No. 55,869

Term of patent 7 years

To all whom it may concern:

Be it known that I, Paul L. Parsons, a citizen of the United States, residing at Belvidere, in the county of Boone and State of Illinois, have invented a new, original, and ornamental Design, for a Casket Handle, of which the following is a specification, reference being had to the accompanying drawing, forming part hereof.

Figure 1 is an elevational view of a casket handle showing my new design.

Figure 2 is a cross-sectional view taken along the line 2-2 of Fig. 1.

The design is especially characterized by the external contour of the cross bar forming the handle proper which is polygonal in cross-sectional shape with alternate flat and concave side surfaces.

I claim:

The ornamental design for a casket handle substantially as shown and described.

PAUL LESTER PARSONS.
